UNITED STATES PATENT OFFICE.

GEORGE SCHNITZLER, OF NEW YORK, N. Y.

ENVELOP.

1,098,175.

Specification of Letters Patent.

Patented May 26, 1914.

Application filed May 31, 1913. Serial No. 770,978.

To all whom it may concern:

Be it known that I, GEORGE SCHNITZLER, a citizen of the United States, and a resident of the city of New York, Arverne, borough of Queens, in the county of Queens and State of New York, have invented a new and Improved Envelop, of which the following is a full, clear, and exact description.

10 Among the principal objects which the present invention has in view are: To provide an envelop having a tearing section reinforced to provide a uniting member, the structure of which is unbroken; to provide in an envelop of the character mentioned means for preventing the introduction within the tearing area, of the letter or inclosure when deposited in the envelop; and to provide means of the character mentioned readily and cheaply applicable to envelops constructed in accordance with the present invention.

One embodiment of the present invention is shown in the accompanying drawings, in which—

Figure 1 is a view of an envelop blank having attached thereto a reinforcing strip constructed and arranged in accordance with the present invention; Fig. 2 is a similar view of a modified form, showing an end fragment of the envelop having said reinforcing strip, the body of the envelop being shown as scored and perforated to facilitate the parting of the tearing strip; Fig. 3 is a similar view of a modified form, wherein the reinforcing strip is shown as applied to the flap and body portion of the envelop blank; Fig. 4 is a detail view, on an enlarged scale, showing in section an end fragment of an envelop constructed and arranged in accordance with the construction shown in Fig. 1, the section being taken as on the line 4—4 in said figure; Fig. 5 is a similar view of the construction shown in Fig. 2, the section being taken as on the line 5—5 in said Fig. 2; Fig. 6 is a similar view of the construction shown in Fig. 3, the section being taken as on the line 6—6 in said Fig. 3.

50 As seen in the accompanying drawings, the envelop blank 11 is of conventional construction. The sheet from which it is cut is previously provided with a suitable number of lines of perforations 12, so located on the sheet that when the blank 11 is cut, the line of perforations 12 is spaced from

the body of the envelop substantially as shown in Fig. 1 of the drawings. The sections of the flap 13 in which the perforations 12 are placed are by this means partially severed. The texture of the material is such, however, that in the ordinary service to which the envelop is put, the material becomes broken, and there exists the danger of the envelop breaking at this point to permit the withdrawal from, or loss of the contents of, said envelop.

It is to avoid the severance of the sections of the flap 13, to which attention is above drawn, that I attach to the flap 13 and to the inner surface thereof, a reinforcing strip 14, constructed of any suitable material, such as a close-woven paper, the weave of the paper providing pliability conjoined with tensile strength.

75 The reinforcing strip is attached to the flap 13 by a suitable adhesive. The strip 14 is furnished with a gummed or coated section 15, the width of which is slightly less than the width between the vertical 80 edge of the body of the envelop and the line of perforations 12.

When the sheet from which the blanks, such as designated by the numeral 11 in the drawings, are cut, has been provided with the perforations 12 and the strips 14, the blanks are cut therefrom as though the strips did not exist. When the edges of the flaps of the envelop have been gummed and the blank is folded to form the envelop of commerce, the coated section 15 is moistened so that it adheres to the inner face of the body portion 11. The adhered portions held by the coated section 15 prevent the intrusion of the contents of the envelop beyond 90 the line of tear or separation provided by the perforations 12. When thus constructed, the envelopes are handled in the usual manner. It will be noted, however, that the inclosure of the envelop cannot 95 pass beyond the line of perforations 12. When the envelop is to be now opened, the end portion having the gummed section 15 is torn from the body of the envelop, the line of tear being controlled by the weakened texture in which the line of perforations 12 is formed.

In certain forms of envelopes, I prefer to add a second line of perforations 16, which perforations in the completed envelop are 110 formed in the body of the blank 11, and flaps 17 and 18, as seen best in Fig. 2 of the

drawings. When now the envelop is folded, the coated section 15 will unite the portions of the body of the blank 11 between the line of perforations 16 and the edge of said body and the coated section of the flap 13. When thereafter the rigid edge thus formed by uniting the coated section and the corresponding portion of the body of the blank, is torn from the envelop, the coinciding lines of perforations 12 and 16 reduce the resistance of the material to the tearing effort.

In Fig. 3 of the drawings, a modification is shown, wherein the strip 19 is substituted for the strip 14. The strip 19 is adhered to the body of the blank 11 to extend across the line of perforations 16, and is adhered to the flap 13 to extend across the line of perforations 12. A coated section 20 is attached to the inner surface of the strip 19, and preferably on the portion thereof which is attached to the body of the blank 11. It will be seen that when thus constructed, the united sections of the flap 13 and the body 25 of the blank 11, between the edge of the folded envelop and the lines of perforations 12 and 16, constitutes a rigid edge, which may be ripped or torn from the body of the envelop. It will further be seen that the

united portions within the envelop, of the strip 19, will prevent the intrusion of the contents of the envelop into the tearing area.

Having thus described my invention, I claim as new and desire to secure by Letters Patent:—

A blank of the character described having a rectangular body portion and flaps extending therefrom and provided with a plurality of lines of perforations, said lines being disposed parallel to the edge of the body portion of said envelop and equally distant therefrom and on opposite sides thereof to coincide when the blank is folded; and an imperforate reinforcing strip to cover said lines of perforations and extending at both sides thereof, said strip having an adhesive surface extending from the edge of the body portion to one of the lines of perforations.

In testimony whereof I have signed my name to this specification in the presence of two subscribing witnesses.

GEORGE SCHNITZLER.
